(57) CLAIM

I claim the ornamental design for a dress, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the patent and Trademark Office patent file or records, but reserves all other copyright rights whatsoever.

FIG. 1 is a front elevation view of the dress showing a first embodiment of my new design;

FIG. 2 is a rear elevation view thereof;

FIG. 3 is a front elevation view of the dress showing a second embodiment of my new design;

FIG. 4 is a rear elevation view thereof;

FIG. 5 is a front elevation view of the dress showing a third embodiment of my new design;

FIG. 6 is a rear elevation view thereof;

FIG. 7 is a front elevation view of the dress showing a fourth embodiment of my new design;

FIG. 8 is a rear elevation view thereof;

FIG. 9 is the front elevation view of the front bodice lining of my new design showing built-in bra cups for FIGS. 1-8;

FIG. 10 is a rear elevation view thereof;

FIG. 11 is the front elevation view of the back bodice lining of my new design showing built-in bra cups for FIGS. 1-8 wherein the bodice lining has been removed and shown separately for ease of illustration and showing logo to be covered by copyright; and,

FIG. 12 is a rear elevation view thereof.

The broken line showing of a human figure is included for the purpose of illustrating the environment of use and forms no part of the claimed design.

Dress to Go logo forming part of the claimed design is a registered trademark Of Roni Swindell.

1 Claim, 12 Drawing Sheets
